HOOK AND EYE

Leo Roseman, 377 S. Harrison St., East Orange, N.J.
Filed Sept. 19, 1963, Ser. No. 310,006
1 Claim. (Cl. 24—228)

This invention relates in general to fasteners of a type shown in, for example, Patent No. 2,282,410 granted to Richard J. Roseman on May 12, 1942 and Patent No. 2,534,064 granted to Leo Roseman on December 12, 1950, the fastener including a plurality of fastener elements such as wire eyes that are attached to one of two parts to be fastened together to cooperate selectively with a hook or the like that is connected to the other of said parts, whereby the parts, which may be for example, two portions of a garment, or two articles, can be adjustably fastened together.

This invention contemplates a fastener of the general character which comprises a base strip of flexible material such as fabric folded in such a way so as to provide a channel extending longitudinally of one side of the strip between two parallel folds in the material, and a plurality of separate fastener elements spaced longitudinally of the strip in the channel so that portions of the side walls of the channel in the zones in which the hooking and unhooking of the fastener elements occurs shall be in effect metallic or have a metallic lining to limit lateral movement of the hook with respect to the eye when the hook is connected to the eye and thus protect the fabric at the side of the channels from tearing strains and from abrasion by the hook.

One object of the invention is to provide a novel and improved eye element for a fastener of the character described having a bar portion extending transversely of the channel for engagement by a complementary hook, and elongated parallel portions perpendicular to said bar portion and extending along and coincidentally with opposite sides of the channel, respectively, and secured by stitches at each of opposite ends of said parallel portions to the strip, so that each fastener element shall be firmly held against movement in all directions in its own plane, the strains imposed upon the fastener elements by the hook shall be distributed in such a way as to reduce the tendency of such strains to tear the fastener elements off said strip and said parallel portions shall protect the folds of the material of the strip against excessive wear and tear from engagement with the hook and shall also accurately guide the bill of the hook into hooking engagement with said bar portion.

A further object is to provide a novel and improved eye element formed of a single piece of wire and having elongated parallel portions connected at one end by a hook-engaging cross bar, and having portions at the other ends of said parallel portions formed to provide elongated loops of a length approximately equal to said parallel portions, so that the ends of the loops provide for stitching of the fastener elements to an article or strip at opposite ends of said parallel portions.

Other objects, advantages and results of the invention will be brought out by the following description in conjunction with the accompanying drawing in which

FIGURE 1 is a composite view on an enlarged scale showing the two sections of the fastener disconnected, with one section in plan and the other section in perspective;

FIGURE 2 is an enlarged plan view of one of the eye fastener elements;

FIGURE 3 is an enlarged transverse vertical sectional view approximately on the plane of the line 3—3 of FIGURE 1;

FIGURE 4 is a fragmentary longitudinal vertical sec-

2

tional view on the plane of the line 4—4 of FIGURE 1 with the two sections of the fastener connected together;

FIGURE 5 is a fragmentary vertical sectional view on the plane of the line 5—5 of FIGURE 4;

FIGURE 6 is a plan view on a reduced scale of a strip of fastener tape constructed in accordance with the invention; and

FIGURE 7 is a fragmentary enlarged plan view of a portion of the fastener strip and one of the fastener elements secured thereto and with the folded portion of the strip at one side of the channel broken away and certain of the stitches shown in horizontal section.

In general, the fastener contemplated by the invention comprises two sections A and B one of which includes one or more rows of eye fastener elements C with which selectively cooperates the other section B which includes a hook D for each row of fastener elements. While I have shown the application of the fastener elements C and hooks D directly to two parts to be connected, for example two parts of a garment or article, the invention more particularly is directed to a fastener wherein the eye fastener elements are connected to a strip or tape 1 that is applied to a portion of a garment or an article such as the end of a brassiere, and the hooks D are secured on a tab or strip 2 which is connected to the other portion of the garment or article, such as the other end of the brassiere.

More specifically describing the invention, the body strip 1 is shown as formed of a strip of flexible material, for example fabric, that is folded longitudinally into two plies along two parallel folds 3, then again folded longitudinally inwardly of each of the folds 3 as indicated at 4 so that portions 5 of the folded strip are folded inwardly onto the main portion of the strip, with the two folds 3 in spaced and parallel relation to each other. Another piece of material 6 is longitudinally folded into two plies to form folds 7 at the longitudinal edges of the piece, said piece 6 being disposed in superposed relation to the main portion of the strip 1 with its folds 7 in spaced and parallel relation to the folds 3 so as to provide two parallel channels E extending longitudinally of the strip 1 at one side thereof and each formed between one of the folds 3 and one of the folds 7 and of a width greater than the width of the bill of the hook D as best shown in FIGURE 5. It should be understood that while two channels have been shown, one channel or more than two channels can be provided, and where only one channel is required, the piece 6 can be omitted and the single channel can be formed between the two folds 3. Also, the channels can be provided in the strip in other ways than by folding as described.

A plurality of the eye fastener elements C are shown as equally distantly spaced apart longitudinally of the strip in each channel. Each eye fastener element is shown as comprising a single piece of wire bent to form a rigid bar portion 8 connected at each end to one end of a straight side portion 9 that is disposed perpendicularly to the bar portion. The wire is bent at the other end of each of the side portions 9 as indicated at 10 to provide a straight portion 11 spaced from and parallel to the corresponding portion 9 and merging into an end portion turned as indicated at 12 into approximate alignment with the bar portion 8.

The distance between the straight side portions 9 is approximately the same as the distance between the folds at opposite sides of a channel E, and the fastener elements are disposed on the strip with the straight portions 9 preferably flush or coincident with the corresponding folds 3 and 7 and with the loop portions 10, 11 and 12 between the main portion of the strip 1 and the in-folded portions 5 and the strip 6, respectively. If de-

sired, the portions 9 might extend beyond the folds into the channels. The fastener elements C are arranged so that the bill of the hook D is passed between the straight side portions 9 as the hook is connected to and disconnected from the hook-engaging bar 8 of the eye fastener element, and the portions 9 are of a length at least equal to the length of the hook bill as best shown in FIGURES 1, 4 and 5. In other words, the portions 9 of all eye elements extend in the same direction from their cross bars 8.

The eye fastener elements are shown as firmly secured on the strip by a plurality of groups F of tying stitches that penetrate the superposed plies of the strip and overlie the portions 10 and 12 at the ends of the loops of the fastener elements. Preferably the tying 15 stitches F form parts of lines of stitches G that extend longitudinally of the strip, one adjacent each of the folds 3 and 7 and passing between the straight portions 9 and loop portions 11 of the fastener elements, or at the outer sides of the portions 9 opposite the fold. These 20 stitches also secure the strip 6 on the main strip 1.

With this construction it will be seen that the eye fastener elements are firmly secured to the strip at two points spaced longitudinally of the straight side portions 9 and said straight side portions 9 form elongated metal 25 portions or "linings" of the side walls of the channels in the zones of movement of the hook bill during the connection and disconnection of the hook to and from the hook-engaging bar 8 of the eye fastener element. These metal portions of the side walls provide rigid 30 guides to direct the hook bill to the bar portion 8 and also limit lateral movement of the hook as can best be seen in FIGURES 5 and 7 as to protect the fabric at the folds 3 and 7 against tearing strains and against 35 abrasion by the hook. The fastener is thus exceptionally strong and durable, and also the metal side portions 9 of the eye elements can be easily detected by the sense of touch of the person attempting to connect a hook to an eye element, which is especially important where the fastener is applied to the back strap of a brassiere and cannot be readily seen. The eye element is held 40 against both tilting out of the plane of the strip and lateral movement on the strip; and the connection of the element to the strip by the spaced groups of tying stitches F provides a strong resistance to pulling of the fastener 45 of the eye element from the strip under tension applied by the hook during use of the fastener.

While FIGURE 1 shows only three fastener elements spaced longitudinally of each row or channel, it should be understood that the invention can be embodied in long strips of fastener tape as shown in FIGURE 6, and such long strips can be used to provide more numerous adjustments of the fastener, or the strips can be cut into sections for making the fasteners like that illustrated in FIGURE 1.

While the now preferred embodiment of the invention has been shown and described, it will be understood by those skilled in the art that modifications and changes in the construction of the eye fastener element and of the fastener strip may be made within the spirit and scope of the invention.

I claim:

An eye fastener element formed of a single piece of wire having end portions and a bar portion therebetween, said bar portion being connected at each of its ends to an elongated straight side portion, said side portions being perpendicular to the bar portion and spaced from and parallel to each other, and there being a loop portion spaced from and approximately parallel to each of said side portions, each loop portion being connected at one of its ends to the corresponding side portion and being connected at its other end to the corresponding end portion of the wire piece, said end portions being disposed in approximate alignment with said bar portion.
